(Cl. D4—2)

FIG. 1

FIG. 2

FIG. 3

FIG. 4

Fig. 1 is a top plan view of a combined sink, work top and drainboard, showing my new design.

Fig. 2 is a front elevational view thereof.

Fig. 3 is an end elevational view taken from left of Fig. 2.

Fig. 4 is an end elevational view taken from the right of Fig. 2.

The dominant features of my design reside in the portions shown in full lines.

I claim:

The ornamental design for a combined sink work top and drainboard, substantially as shown and described.
